UNITED STATES PATENT OFFICE

104,341

DESIGN FOR A METAL CONTAINER

Martha H. Connor, Baltimore, Md., assignor to Owens-Illinois Can Company, Wilmington, Del., a corporation of Delaware

Application March 22, 1937, Serial No. 68,314

Term of patent 7 years

To all whom it may concern:

Be it known that I, Martha H. Connor, a citizen of the United States, residing at Baltimore, in the State of Maryland, have invented a new, original, and ornamental Design for a Metal Container of which the following is a specification, reference being had to the accompanying drawing forming a part thereof.

In the drawing:

Fig. 1 is a top plan view of a metal container showing my new design.

Fig. 2 is an end elevational view thereof.

I claim:

The ornamental design for a metal container substantially as shown.

MARTHA H. CONNOR.
